UNITED STATES PATENT OFFICE.

TOM SETTLE AND WILLIAM ALBERT PADFIELD, OF EXETER, ENGLAND.

PROCESS OF MANUFACTURING COAL-GAS.

SPECIFICATION forming part of Letters Patent No. 762,495, dated June 14, 1904.

Application filed May 23, 1903. Serial No. 158,388. (No specimens.)

To all whom it may concern:

Be it known that we, TOM SETTLE, a resident of Haven Villa, Haven Banks, Exeter, and WILLIAM ALBERT PADFIELD, a resident of 5 Southernhay, Exeter, in the county of Devon, England, subjects of the King of Great Britain, have invented certain new and useful Improvements Relating to the Manufacture of Coal-Gas, of which the following is a specification.

10 In the accompanying drawings we show at Figure 1 a horizontal retort in cross-section to illustrate in diagrammatic form the result of the present plan of charging retorts in bulk, and in Fig. 2 we show in sectional elevation an apparatus which illustrates our new method of procedure.

The details of construction are of minor importance and capable of modification in various respects.

20 The method of charging horizontal retorts in bulk in the manufacture of illuminating coal-gas is wasteful. Also during the discharging and charging the retorts cool down considerably, requiring some time to reheat 25 them, with a consequent loss in the production of gas.

Now the object of the present invention is to overcome these disadvantages while at the same time simplifying the process of carbonizing coal. Among the resulting advantages 30 are a considerable increase in the yield of gas per ton of coal, a gas of higher value, an improved quality of coke, an economy of labor, and a reduction in the cost of raw material, as 35 by this invention a waste product in the shape of small or dust coal or slack may be used.

To this end our invention consists in so gradually building up the coal in the retort that while the greater portion of the mass therein 40 is kept incandescent there is always an uncarbonized layer at the top in the best position for conversion into gas of high quality, and free communication is maintained between this layer and the outlet-pipe of the 45 retort.

Referring then to Fig. 1, A is the retort of the ordinary D form, and B C represent the 50 charge of coal lying on the floor of the retort. The retort being heated externally, the portions of the charge lying next the walls of

the retort become comparatively quickly carbonized and form a mass of red-hot coke, as represented by B. As in this case the carbonization is effected from the outside inward a core of uncarbonized coal will be left, 55 as represented by C, surrounded by the red-hot mass B. As the core C gradually becomes carbonized the gas driven off has to pass through the mass B and in so doing portions of the gas become decomposed and lose 60 their illuminating properties and to such an extent that it does not pay to keep on the carbonization until the whole mass is completely carbonized. It results, therefore, that a portion of the core C remains uncarbonized, and 65 thus a loss of gas takes place, while much of the gas driven off is impaired and is of poor quality.

Referring now to Fig. 2, which illustrates the mode of procedure according to our invention, D is the retort, E the mass of red-hot coke, and F the uncarbonized coal. As before stated, the mass is gradually built up in the retort; but the uncarbonized coal is always at the top, as at F, and the gas is driven 70 off direct to the ascension-pipes without passing through or in contact with the red-hot mass of coke. The gas thus retains all its illuminating properties and is not impaired by passing through a red-hot mass of coke. 75 This Fig. 2 also shows the character of the apparatus which we employ for the purpose of our invention. G will represent the retort-setting, which will be of any suitable character. The retort will preferably consist of a 80 vertical portion H at top of about one-half the length of the retort and an inclined portion J below of about one-fourth the length of the retort, the remaining fourth portion K, between the parts H and J, being curved, as 85 shown. The vertical portion will be slightly taper, expanding downward, and the inclined portion will be of the larger diameter and extend outside the setting, where it will be provided with a mouthpiece L, having a door or 90 cover of suitable construction. At top this retort will be provided with another mouthpiece M, with which is connected a feeding appliance for the coal and the ascension-pipe 95 N or its equivalent. The feeding appliance 100

will consist of a hopper O to receive the fine coal and provided with a cylindrical extension P in connection with the mouthpiece M. This hopper is placed, preferably, centrally over 5 the mouthpiece, as indicated. In the cylinder P is arranged a measuring and sealing device, which will consist of a pair of conical plungers or pistons Q, mounted on the same rod R at suitable distances apart and working 10 easily in the cylinder P. The stroke of the pistons will be such that the top one will pass out of the cylinder P at top to admit of coal from the hopper O passing in between the pistons, and the lower one will pass out of the 15 cylinder P at the bottom to allow of the discharge of coal into the retort, and thus one plunger Q always remains in the cylinder P, so that the retort will be sealed and the passage of gases from the retort through the hopper 20 will be prevented. The plungers Q will be operated vertically in any convenient manner from a prime mover. The lower conical plunger will cause the coal to fall toward the walls of the retort and form, in effect, the cup-shaped pocket of uncarbonized coal, as indicated at F, on the top of the red-hot mass of coke E. This pocket will act as a kind of caldron in which the tar produced by carbonization will be decomposed, the more volatile 25 parts distilling off in the form of gas of high quality, and thus a great increase in the yield of gas of superior quality will be obtained.

In charging the retort care should be taken 30 not to fill it to such a height as to obstruct the passage of the gas to the outlet-pipe, but that the whole surface of the pocket-like or caldron-like layer of uncarbonized coal should be exposed to the space in the upper part of 35 the retort in which the gas is collected for passage to the outlet-pipe.

The small coal used cokes rapidly and produces a superior quality of coke. The discharge is easily effected through the bottom 40 mouthpiece upon removing a plate S, which serves to support the mass of coke clear of the cover until the cover is removed.

When the coke is discharged, the plate S is replaced and the operation of carbonizing goes 45 on as before.

The retorts according to our invention are not allowed to cool down, and the life of the retort is much longer in consequence. There is also an entire absence of the smoke that is 50 usually seen when charging retorts in the ordinary way.

The coal or slack may be tipped into a pit in the ground and raised by an elevator to a conveyer, which will convey it along the top 55 of the settings to the hopper of each retort.

According to this process there is gradually built up in the retort a homogeneous columnar mass of incandescent material having at the top a cup-shaped depression which

forms a kind of caldron for the reception of successive layers of fresh uncarbonized coal, from which there is directly produced a very rich illuminating-gas free from tar, all the constituents of the coal ordinarily converted into tar being in this case converted into gas. 65 By thus building up gradually and maintaining in the retort a column of red-hot material and feeding the fresh coal to the top of this column the gas produced is prevented from passing through a red-hot mass and is caused 70 to pass directly to the ascension-pipe at the top of the retort, which is a most important feature. This process also does away with the core of uncarbonized material, which is wasted in the usual methods in which the gas 75 is generated from the outside toward the center of the retort.

By means of this invention great economy of production will be effected both in materials and labor with greatly improved products, whereby further economy will result. 80

What we claim as our invention, and desire to secure by Letters Patent, is—

1. In the manufacture of illuminating-gas from coal, the mode of carbonizing coal in vertical retorts, as herein described, consisting in introducing the coal into the top of the retort intermittently in small quantities at regular short intervals, and so building up gradually a mass of incandescent material, with a continuous layer of coal in the process of carbonization on the top, whence the gas is driven off upward without coming into contact with or passing through the incandescent mass of coke in the retort. 90

2. In the manufacture of illuminating-gas from coal, the mode of carbonizing coal in vertical retorts, consisting in introducing coal into the retort in such a manner that the coal will fall toward the walls of the retort and so build up a mass of incandescent material with a cup-shaped layer of uncarbonized coal at the top extending to the walls of the retort, as and for the purpose set forth. 105

3. In the manufacture of illuminating-gas from coal in upright retorts, the mode of supplying the coal to such retorts which consists in introducing it in measured quantities toward the walls of the retort in such manner as to produce a cup-shaped layer of uncarbonized coal on the top of the gradually-increasing mass of incandescent material contained in the retort and to leave a space around the walls of the retort above said layer, as and for the purpose set forth. 110

In testimony whereof we have signed our names to this specification in the presence of two subscribing witnesses.
